UNITED STATES PATENT OFFICE.

FRANK H. SMITH, OF DETROIT, MICHIGAN.

AUTOMATIC SPARK-RETARDER.

1,368,581.

Specification of Letters Patent. Patented Feb. 15, 1921.

Application filed October 9, 1919. Serial No. 329,577.

To all whom it may concern:

Be it known that I, FRANK H. SMITH, a citizen of the United States, residing at Detroit, county of Wayne, State of Michigan, have invented a certain new and useful Improvement in Automatic Spark-Retarders, and declare the following to be a full, clear, and exact description of the same, such as will enable others skilled in the art to 10 which it pertains to make and use the same, reference being had to the accompanying drawings, which form a part of this specification.

This invention relates to mechanism designed to automatically retard the spark and prevent a premature explosion during the cranking of an internal combustion engine, and is here shown as being attached to the engine of a Ford car in connection with 20 which it is particularly adapted to be used.

In the drawings,—

Figure 1 is a front elevation of a Ford motor taken on the line I—I of Fig. 2.

Fig. 2 is a fragmentary cross-sectional 25 view.

Fig. 3 is an illustration of the band identified by the letter *i*.

Fig. 4 shows a modified form of the ratchet carried by the starting crank.

30 In the drawings, *a* represents the conventional motor assembly, *b* the commutator, *c* the rod which constitutes the connection means between the spark-control lever on the steering wheel and the commutator. *d* is 35 the starting crank mounted in bearings *e* and provided at its inner extremity with a starting ratchet *f* which is adapted to engage a pin *g* carried by the crank shaft *h*.

A band *i* is provided which encircles the 40 starting crank and in use on a Ford car would be of the form here shown adapted to encircle the starting ratchet *f* and to be firmly held in place thereto. This band is provided with lugs *j* in such number as may 45 be described, four being here shown. The band here illustrated is made in halves adapted to be secured together by means of bolts *k*. A preferred form might be to provide a special design of starting ratchet as 50 shown in Fig. 4, in which the ordinary form of ratchet adapted to be secured to the starting crank would be provided with integral radial lugs *l*. This provision of radial lugs on the starting ratchet would prevent any 55 trouble which might arise due to the loosening of the clamp band *i* as the starting

ratchet would be held in place in the usual manner now provided.

There is likewise provided a system of linkage attached to the front of the motor 60 connected at one end with the rod *c* and adapted to intercept and be set in motion by lugs *j* or *l* carried by the band *i* or the starting ratchet *f*.

Comprising this linkage is a lever *m* pivoted to a bolt or stud *n*. This lever *m* is provided at its lower extremity with a friction roller *m*². The bolt *n* is one now used in Ford construction and is merely extended to provide pivoting means for such lever *m*. 65 A transverse lever *o* is pivotally connected with lever *m* at one end, the other end being formed to receive the rod *c*, as shown. The lever *o* is longitudinally adjustable so as to provide means to regulate the degree of 70 75 retardation.

The commutator here shown is adapted to be moved by the rod *c* in the direction of retardation of the spark.

It is thought that the operation of the device is apparent from the above description. 80

In the cranking of the motor it is desirable that combustion in the cylinders be delayed so as to prevent the occurrence of a premature explosion which might result in 85 a "back kick" with consequent injury to the one starting the motor.

This has proved to be a frequent occurrence in the hand cranking of internal combustion engines and the sprained and broken 90 wrists and arms resulting therefrom are without number. The spark is advanced too far, either through oversight, ignorance or faulty connecting means, and the explosion occurs before the piston has arrived at 95 the top-most point of the compression stroke.

When it is desired to start the motor, starting crank *d* is pushed inward until the ratchet *f* engages the pin *g* of the crank shaft. This brings the lugs *j* carried by the band *i* in position to be intercepted upon rotation of the starting crank by the friction roller *m*² carried at the lower end of lever *n*. When the starting crank is rotated in 100 direction to start the motor upon the engagement of lugs *j* with friction roller *m*², lever *m* is swung to the position shown in dotted outline in Fig. 1, thus allowing the starting crank and crankshaft to continue 105 rotation. It will be seen that in this position of the lever *m*, the commutator is actu- 110

ated to retard the production of the spark and during the time the linkage remains in this position the explosion in the combustion chambers will be delayed until the piston has reached its maximum compression stroke. Should there be an advance of the spark due to any cause, with consequent actuation of the linkage further rotation of the starting crank would bring the lugs 10 into engagement with the friction roller m^2 again moving the commutator so as to retard the spark.

Claims:

1. In a spark-retarding attachment for 15 "Ford" engines, a hand crank, a clamping ring provided with radially-projecting lugs, such ring adapted to be removably secured to the hand-crank at the ratchet end thereof, a system of linkage adapted to be pivoted to the engine, one end of such linkage adapted to be pivoted to the commutator, the other end of said linkage adapted to be 20 positioned in the path of revolution of the

radially-projecting lugs on the clamping ring so as to intercept the same and be 25 moved aside thereby when the hand-crank is rotated in the cranking of the engine, in such a manner as to actuate such linkage to move such commutator so as to retard the production of a circuit therethrough.

2. In a spark-retarding attachment for 30 "Ford" engines, a hand-crank, a clamping ring provided with radially-projecting lugs, such ring adapted to be removably secured to such hand-crank at the ratchet end thereof, a commutator, means for actuating such commutator so as to retard or advance the formation of a spark therethrough, such means adapted to be actuated so as to move 35 said commutator to the retard position by intercepting the revolution of the lugs on the hand-crank during the rotation of the crank in the cranking of the engine.

In testimony whereof I sign this specification.

FRANK H. SMITH.
